RADIO CABINET

Melvin H. Boldt, 933 N. Glenayre Drive, Genview, Ill.
60025, and George A. Wilson, 738½ Hinman Ave.,
Evanston, Ill. 60402

Filed May 27, 1969, Ser. No. 17,374

Term of patent 14 years

Int. Cl. D14—03

U.S. Cl. D56—4

FIG. 1

FIG. 2

FIG. 3

FIG. 4

FIG. 1 is a front elevational view of our design for a radio cabinet;

FIG. 2 is a side elevational view thereof;

FIG. 3 is a top plan view thereof; and

FIG. 4 is a perspective view showing the top, side and rear thereof.

A portion of FIG. 1 is diagonally lined to indicate transparency. Portions of the figures are shaded to indicate contrast in appearance.

We claim:

The ornamental design for a radio cabinet, substantially as shown and described.
